UNITED STATES PATENT OFFICE.

HERMANN MÜLLER, OF CHEMNITZ, GERMANY.

HORSESHOE-CALK.

No. 837,488.

Specification of Letters Patent.

Patented Dec. 4, 1906.

Application filed December 7, 1905. Serial No. 290,696.

To all whom it may concern:

Be it known that I, HERMANN MÜLLER, merchant, a subject of the German Emperor, and a resident of Chemnitz, Saxony, Germany, have invented new and useful Improvements in Horseshoes, of which the following is a specification.

This invention relates to hollow calks which are to be inserted into horseshoes made of steel, the novelty of this invention being in that the walls connecting the calk-tread to the insertion-shaft are curved in a corrugated way, whereby said walls are capable of resisting greater strains, and consequently less likely to break off.

The accompanying drawings show a constructional form of the invention, namely:

Figure 1 is a perspective rear view, while Fig. 2 shows a front view of the same. Fig. 3 shows a plan, and Fig. 4 a cross-section, of how the hollow calk is to be inserted into the horseshoes.

The hollow calk, which is made of steel, comprises the conical shaft *a* and the walls *c*,

which connect the shaft with the tread *b*. The side walls *c* are shaped in corrugated fashion, whereby they are strengthened, and thus capable of greater resistance to breaking strains. In order to increase the resistance of the tread *b*, the latter is also curved. The cross-section of the shaft *a* may be either semicircular, square, oval-shaped, or the like, or even two shafts may be used.

Having fully described my invention, what I claim, and desire to secure by Letters Patent, is—

A hollow steel calk for horseshoes comprising, a shaft *a* the corrugated walls *c* said walls connecting the shaft with the tread *b*, substantially as described and shown and for the purpose set forth.

In testimony whereof I have hereunto set my hand in the presence of two subscribing witnesses.

HERMANN MÜLLER.
